DIAL TELEPHONE PAY STATION

George A. Long, Hartford, Conn., assignor to The
Gray Telephone Pay Station Company, Hartford,
Conn., a corporation of Connecticut

Application July 13, 1936, Serial No. 90,303

10 Claims. (Cl. 179—100)

My invention relates to that class of telephone apparatus which are automatic in character and which are provided with means for collecting pay for the use of the apparatus, and an object of my 5 invention, among others, is the production of a dial mounting for such apparatus which mounting shall be comparatively light in structure and particularly secure so far as unauthorized access to the money compartment is concerned.

10 A portion of a telephone apparatus embodying my invention and in the construction and use of which the objects herein set out, as well as others, may be attained is illustrated in the accompanying drawing in which

15 Figure 1 is a front view of the upper part of the case of an automatic pay station telephone embodying my invention.

Figure 2 is a side view of the same.

Figure 3 is a front view on enlarged scale of 20 the dial and its mounting with parts broken away to show construction.

Figure 4 is a view in section on a plane denoted by the dotted line 4—4 of Fig. 3.

In the accompanying drawing the numeral 5 25 denotes the upper part of the instrument case of an automatic telephone pay station which is of ordinary construction and which is secured to a back plate 6, said case being provided with a coin plate 7 in a manner common to structures 30 of this class.

A dial case or receptacle 8 is secured to the front face of the instrument case 5 near the upper part thereof this case embodying the principal features of my invention. It is of generally ring-like shape embodying an indicia ring support 9 35 which is round when viewed from the front, this terminating at the back in a calling case support 10 which is adapted to be secured squarely against the front face of the case 5, and as shown in Figs. 40 2 and 4 of the drawing.

The support 9 has a lip 11 extending around its periphery at the front thereof and surrounding a seat 12 for an indicia ring 13. This ring has 45 locating posts 14 projecting inwardly from the back face thereof, these posts preferably, and as shown herein, being three in number located at different distances apart to compel the plate to be placed in a certain position when secured. The ring 13 bears characters 15 arranged in a manner common to structures of this type and it is essential that when secured in place this ring shall be always in the position shown and have proper relation with respect to a finger stop 16 to be more particularly hereinafter described. Lugs 50 55 17 project radially inward from the ring or sup-

port 9, these lugs being bored at 18 and counter-bored at 19, the posts 14 projecting into the counter-bored portions and screws 20 projecting from the rear of the lugs through the holes 18 and into the posts 14, and as shown in Fig. 4 of the drawing. It will be noted that these screws 20 are covered by the front face of the instrument case 5 so that access cannot be had to them and the indicia ring 13 cannot therefore be removed without removing the entire structure from the front of the case 5.

Ears 21 project from the back or lower part of the lugs 17 and an ear 22 projects inwardly from the inner wall of the support 10, there being two of the ears 21 and one ear 22 evenly spaced apart 15 and forming seats for a calling case 23 which is secured in place within the supports 9—10, said calling case also being seated upon a ledge 24 projecting from the lug 17 located at the upper part of the structure, and as shown in Fig. 3 of the drawing. A chamber 25 is formed in the front face of the case 5 and calling mechanism secured to the back face of the case 23 is located in this chamber. Screws 26 project through the back wall of the chamber 25 into the calling case 23, 25 these screws passing through holes formed through the ears 21—22, as shown in Figure 3 of the drawing.

Lugs 27—28 project inwardly from the inner wall of the calling case support 10, the lug 27 30 being located at the bottom of the structure and the lugs 28 being of similar formation located opposite one another near the upper part of the device. Screws 29 extend through the front wall of the case 5 into threaded openings in said lugs 35 27—28, as shown in Figures 3 and 4 of the drawing, for the purpose of securing the structure as a whole in place on the face of the case 5.

From this it will be seen that the dial mounting as a whole is secured in place and can only be 40 removed by access from within the case 5, the calling case 23 being secured in a similar manner and access to the screws 20 that secure the ring 13 can be had only by removal of the entire mounting from the front of the case. 45

The ring 13 has a notch 30 through which the finger stop 16 hereinbefore referred to extends, and as shown in Fig. 1 of the drawing, this serving to properly position the calling case 23 to receive the screws 26. A finger dial 31 is rotatably mounted on the front of the calling case and underlying the finger stop 16 in a manner common to telephone apparatus. 50

I claim:

1. In combination with the instrument case 55

for a telephone pay station, a dial mounting therefor, said mounting including a dial case, an indicia ring mounted on the front face of said dial case, fastenings projecting forwardly through 5 said dial case to engage said indicia ring to secure the latter in place, the back ends of said fastenings being covered by said instrument case, a calling case including a finger dial secured to said dial case by fastenings projecting forwardly 10 from within the instrument case, and means for securing said dial case in place.

2. In combination with the instrument case for a telephone pay station, a dial mounting therefor, said mounting including a dial case, an indicia ring mounted on the front face of said dial case, fastenings projecting from the back of said dial case forwardly into engagement with said indicia ring to secure the latter in place, the back ends of said fastenings being covered by the 15 front face of the instrument case, a calling case including a finger dial secured to said dial case, and means for securing said dial case in place.

3. In combination with the instrument case for a telephone pay station, a dial mounting therefor, said mounting including a dial case, an indicia ring mounted in the front face of said dial case, fastenings projecting from the back of said dial case forwardly into engagement with said indicia ring to secure the latter in place, the back 20 ends of said fastenings being covered by the front face of the instrument case, a calling case including a finger dial secured to said dial case, and fastenings extending from within the instrument case into engagement with said dial case to secure 25 the latter in place.

4. In combination with the instrument case for a telephone pay station, a dial mounting therefor, said mounting including a dial case, an indicia ring mounted on the front face of said dial 30 case, fastenings projecting forwardly through said dial case to engage said indicia ring, the back ends of said fastenings being covered by said instrument case, a calling case including a finger dial secured to said dial case by fastenings 35 projecting forwardly from within the instrument case, and means for securing said dial case in place.

5. In combination with the instrument case for a telephone pay station, a dial mounting therefor, said mounting including a dial case, an indicia ring mounted on the front face of said dial case, fastenings projecting forwardly through said dial case into engagement with said indicia ring to secure the latter in place, the back 40 ends of said fastenings being covered by the instrument case, a calling case including a finger dial secured to said dial case by fastenings projecting from within the instrument case through 45 said dial case into engagement with said calling case, and means for securing the dial case in place.

6. In combination with the instrument case for a telephone pay station, a dial mounting therefor, said mounting including a dial case, an 50

indicia ring mounted on the front face of said dial case and having posts extending into holes in said dial case, fastenings projecting forwardly through said dial case into engagement with said posts, said fastenings being covered by said instrument case, a calling case including a finger dial secured to said dial case by fastenings projecting forwardly from within the instrument case into engagement with said calling case, and means for securing said dial case in place. 5 10

7. In combination with the instrument case for a telephone pay station, a dial mounting therefor, said mounting including a dial case, an indicia ring mounted on the front face of said dial case and having positioning posts differently spaced apart to compel insertion of the indicia ring in a certain position, fastenings projecting forwardly through said dial case into engagement with said posts, the back ends of said fastenings being covered by said instrument case, a calling case including a finger dial secured to said dial case by fastenings projecting forwardly into engagement with said calling case, and means for securing said dial case in place. 15 20

8. In combination with the instrument case for a telephone pay station, a dial mounting therefor, said mounting including a dial case of ring shape, lugs projecting radially inward in said dial case, an indicia ring mounted on the front face of said dial case, fastenings projecting forwardly through said lugs into engagement with said indicia ring, said fastenings being covered by said instrument case, a calling case including a finger dial secured to said dial case, and means for securing 30 35 said dial case in place. 35

9. In combination with the instrument case for a telephone pay station, a dial mounting therefor, said mounting including a dial case of ring-like form with ears projecting radially inward forming seats, an indicia ring mounted on the front face of said dial case, fastenings projecting from the back of said dial case forwardly into engagement with said indicia ring to secure the latter in place, the back ends of said fastenings being covered by said instrument case, a calling case including a finger dial resting against said seats, fastenings projecting forwardly into engagement with said calling case to secure it in place, and means for securing said dial case in place. 40 45

10. In combination with the instrument case for a telephone pay station, a dial mounting therefor, said mounting including a dial case of ring-like form, ears projecting inwardly within said dial case and forming seats, an indicia ring mounted on the front face of the dial case, fastenings projecting from the back of said dial case forwardly into engagement with said indicia ring to secure the latter in place, a calling case including a finger dial resting against said seats, fastenings projecting forwardly from within the instrument case through said ears into engagement with said calling case, and means for securing said dial case in place. 50 55 60

GEORGE A. LONG.
